UNITED STATES PATENT OFFICE.

WILLIAM L. BROWN, OF GLOVERSVILLE, NEW YORK

TRAFFIC GUIDE OR SIGNAL.

1,414,173.

Specification of Letters Patent. Patented Apr. 25, 1922.

Application filed October 4, 1921. Serial No. 505,364.

To all whom it may concern:

Be it known that I, WILLIAM L. BROWN, a citizen of the United States, and a resident of Gloversville, in the county of Fulton and State of New York, have invented a new and Improved Traffic Guide or Signal, of which the following is a description.

My invention relates to a guide or signal for use in directing traffic in streets and highways and particularly the invention relates to a suspended device for the indicated purpose.

The general object of my invention is to provide a traffic guide or signal of exceedingly simple construction adapted to display at its four sides a desirable legend, such as "Keep to the right" and having means to illuminate the interior, as well as novel means to suspend the device on a cable, such as the cable of an electric lighting system, a further purpose being to provide an arrangement affording ready access to the light.

Reference is to be had to the accompanying drawings, it being understood that the drawings are merely illustrative of one example of the invention.

Figure 1 is a perspective view of a traffic signal or guide embodying my invention;

Figure 2 is a vertical section thereof on an enlarged scale.

Figure 3 is an enlarged plan view; and Figure 4 is an inverted plan view.

In carrying out my invention in practice in accordance with the illustrated example, a body 10 is provided advantageously flaring downwardly and is provided on the four sides with windows 11 in which celluloid or other transparent medium may be employed. The body 10 has a central bore 12 which is open at the lower end. The forming of the window leaves corner posts 10^a sustaining the top 13 through a vertical hole 14 in which a cable 15 passes downwardly to the interior

of the body. The cable is indicated as an electric cable carrying at its lower end an electric lamp 16.

The body 10 is supported on the cable 15 as follows: An elongated sleeve 17 is provided on the cable above the lamp socket 18 and the top 13 of the body 10 rests on said sleeve. Advantageously, in practice, the top 13 is slidable on the cable so that the body 10 may be raised more or less for increasing the accessibility of the lamp 16 for renewing the bulb.

The cable is of the type adapted to be held by a supporting wire, a fragment of which is indicated at 19.

I would state in conclusion that while the illustrated example constitutes a practical embodiment of my invention, I do not limit myself strictly to the exact details herein illustrated, since, manifestly, the same can be considerably varied without departure from the spirit of the invention as defined in the appended claims.

Having thus described my invention, I claim:

1. A traffic guide comprising a hollow body open at the bottom to afford access thereto and provided with side windows, bearing a guiding legend, a suspension cable passing slidably through the top of the body, an illuminating means on said cable within said body, and a sleeve fitted on the cable above said illuminating means, said body at the top thereof having support on said sleeve and freely slidable vertically.

2. A traffic guide comprising a hollow body open at the bottom to afford access thereto and provided with side windows, bearing a guiding legend, a suspension cable passing through the top of the body, a lamp socket on said cable within said body, and means on said cable at the interior of the body above said socket affording support for said body.

WILLIAM L. BROWN.
